RIGID PANEL CONSTRUCTION

Charles C. Leach, St. Louis, Mo., assignor to Glaser Products Corp., St. Louis, Mo., a corporation of Missouri

Filed Jan. 6, 1964, Ser. No. 335,910
1 Claim. (Cl. 189—46)

The invention relates to panels equipped with handles such as doors and consists particularly in improved means for rigidifying a panel fabricated of light gauge sheet metal.

Doors for many types of cabinets are formed by bending a flat sheet of light gauge metal at right angles to the plane of the sheet to form flanges along both sides and ends of the door but disconnected at the corners. Doors so made are lacking in rigidity in that the panel can be readily deformed along its diagonals even though the sides and ends are rigidified by their angle formation, since the side and end flanges are not connected at the corners.

It is accordingly a main object of the invention to provide means for rigidifying doors or similar panels formed of flat sheets of light gauge metal bent at right angles to their general planes to form flanges along their sides and ends but discontinuous at their corners.

It is a further object to provide structure in which the means for rigidifying such doors or panels is a door handle.

It is an additional object to provide a handle which will function as a torque tube to resist twisting of such sheet metal doors along their diagonals.

The foregoing and additional more detailed objects and advantages are achieved by the construction described hereinafter and illustrated in the accompanying drawings in which:

FIG. 1 illustrates the front of a cabinet provided with doors embodying the invention.

FIG. 2 is an enlarged horizontal sectional view along line 2—2 of FIG. 1.

FIG. 3 is an enlarged vertical sectional view along line 3—3 of FIG. 1.

FIG. 4 is a fragmentary vertical sectional view along line 4—4 of FIG. 2.

Cabinet 1 is of sheet metal construction and is provided with an opening 3 in its front wall 5, the metal of wall 5 being bent inwardly as at 7 at right angles to the general plane of wall 5 to form a flange at each side of opening 3. Opening 3 is closed by a pair of doors 9, 9 of sheet metal construction consisting of a rectangular main plate 11, the margins of which are bent inwardly at 13, 15, 17 and 19 at right angles to the general plane of plate 11. The outer vertical flanges 15 of the doors are connected by piano hinges 21 to the inward flanges 7 of the cabinet front wall. Flanges 13, 15, 17 and 19 are not connected to each other at their adjacent ends so that, although they help to rigidify the door in directions parallel to theirs, the door, in the absence of other rigidifying means, could be twisted about its diagonals connecting the corners.

For rigidifying the door, and at the same time providing it with a handle, I form a handle comprising a seamless tube 23, the ends 25 of which are flattened and bent at right angles to the axis of the tube. Plate 11 of the

2

door is slotted as at 27 along its intersection with top and bottom flanges 17 and 13 sufficiently to permit the insertion therethrough on a diagonal, i.e., at an angle other than 90° with the plane of plate 11, as best seen in FIG. 2, of the flattened ends 25 of handle 23, 25, the inner extremities 29 of which are cut on a corresponding diagonal for registry with the inner margins of flanges 13 and 17. Flattened end portions 25 are rigidly secured to the inner surfaces of flanges 13 and 17, respectively, at points spaced apart lengthwise of the flange, as by screws 31. With this construction, handle 23, 25 because of its resistance to torsion prevents skewing of upper and lower flanges 17 and 13 relative to each other and thus prevents any twisting of plate 11 of the door. It will be evident that the smaller the acute angle between the inner edges of flattened elements 25 and the plane of the door, the greater will be the rigidifying effect, which will be minimized as this angle approaches 90°. An angularity in the order of 45° is the optimum whereby the lengths of the flattened end portions 25 of the handle can be kept at the minimum consistent with providing sufficient clearance between the plane of the door and the tubular portion of the handle. any attempt to twist the door about its diagonals will be strongly resisted by the resistance of flattened ends 25 to rotation relative to tube 23 and to each other. Because of their method of securement to the door they provide an uncommonly good handle, the tubular portion of which is smooth and easy to effectively grasp.

The details of the construction may be modified substantially without departing from the spirit of the invention and the exclusive use of such modifications as come within the scope of the appended claim is contemplated.

What is claimed is:

A panel comprising a substantially rectangular plate 35 with flanges formed along its margins by bending the margins of said plate substantially at right angles to the general plane thereof, and a handle-brace of rigid construction comprising a tube extending substantially parallel to the plane of said plate and to two of the margins thereof, with its end portions flattened and bent substantially at right angles to the axis of said tube, said tube being spaced from said plate in a direction opposite from that of said flanges, said end portions intersecting said plate at an angle other than 90° with the general plane thereof and being secured to the inner surfaces of the flanges along the other two margins of said plate at points spaced apart lengthwise of said flanges, said plate being slotted along its intersections with said last named flanges to accommodate the passage through said plate of said flattened end portions and their securement against the inner surfaces of said flanges.
